UNITED STATES PATENT OFFICE.

RUSSELL K. NASH, OF SOMERVILLE, MASSACHUSETTS, ASSIGNOR TO LAMB & NASH COMPANY, OF BOSTON, MASSACHUSETTS, A CORPORATION OF MAINE.

CORNER-BEAD.

1,206,130.

Specification of Letters Patent. Patented Nov. 28, 1916.

Application filed August 18, 1916. Serial No. 115,652.

To all whom it may concern:

Be it known that I RUSSELL K. NASH, a citizen of the United States, and a resident of Somerville, in the county of Middlesex and State of Massachusetts, have invented an Improvement in Corner-Beads, of which the following description, in connection with the accompanying drawings, is a specification, like characters on the drawings representing like parts.

This invention relates to a metal corner bead for use in buildings, and has for its object to provide a superior corner bead at a minimum expense. To this end, the corner bead is provided with a substantially flat body portion from which extend arms or legs, which normally lie in the plane of said body portion and which are spaced apart a distance substantially equal to the width of one of said arms, and the latter are then cut to form tongues or fingers, which are bent or folded substantially parallel with the arms to form extensions of the latter, and thus provide the corner bead with arms which are of the desired or standard length and composed of members or sections of different widths. The arms thus formed are bent at an angle to the plane of the body portion with alternate arms on opposite sides of said plane. The body portion is preferably provided with a longitudinally extended fold or bead, which projects on opposite sides of the plane of the body portion so as to provide a substantially T-shaped body portion of maximum strength. The tongues or fingers being formed from the arms or legs, leave a space or opening in the arms for the entrance of plaster, and the corner bead is thereby provided with bonding apertures between the arms or legs and additional bonding apertures in the arms themselves, whereby a superior bonding or adhesion of the plaster to the corner bead is obtained.

The particular features of this invention will be pointed out in the claims at the end of this specification.

Figure 1 represents a portion of a building provided with a corner bead embodying this invention. Fig. 2, a side elevation of a portion of the corner bead shown in Fig. 1. Fig. 3, a portion of the corner bead as it appears before the arms are cut from the fingers. Fig. 4, a view like Fig. 3 with the fingers cut from the arms and folded sub-

stantially parallel therewith. Fig. 5, an end view of Fig. 4, and Fig. 6, a section of the completed corner bead shown in Figs. 1 and 2, taken on the line 6—6, Fig. 2, the corner of the building being shown in plan.

60

Referring to the drawing and especially Figs. 1, 2 and 5, *a* represents the substantially flat body portion, which is of substantial width and is for the best results provided at one edge with a longitudinally extended fold *b* forming a hollow bead, and said body portion has extended from its other edge a plurality of arms or legs *c*, which are spaced apart and separated by spaces *d* of a width substantially equal to the width of one of the arms or legs *c*. The condition of the corner bead as thus far described is illustrated by Fig. 3. The arms or legs *c* are then cut in a manner well understood, to form tongues or fingers 10, which are of sufficient length to enable them to be bent and folded substantially parallel with the arms *c* and to project beyond the lower edges of the latter, as represented in Fig. 5. The arms *c* and their projecting fingers 10 are then bent at an angle to the body portion *a*, and preferably alternate arms and fingers are bent in opposite directions, so that they extend on opposite sides of the plane of the body portion *a*, as represented in Figs. 1, 2 and 6, in which condition, the corner bead is ready for application to the corner of the building 12, to which it is secured by nails or like fastening devices driven through holes 13 in the fingers 10.

100

105

By forming the fingers 10 from the arms or legs *c*, and folding the fingers so as to project beyond the lower edges of the arms, the corner bead is provided with arms composed of members or sections of different widths, which coöperate to form an arm of the desired or standard length, with a minimum amount of metal, inasmuch as a saving in stock is effected over an arm of the same length and of uniform width, which saving is measured in area by the width of the arm *c* multiplied by the distance the finger overhangs the lower edge of the arm or leg *c*.

It will also be noticed that when the fingers 10 are formed, there is left in the arms *c* openings 14 into which the plaster can enter, and these openings together with the spaces *d* provide the corner bead with

110

bonding apertures, by means of which a superior bonding of the plaster to the corner bead is obtained. It will be observed also that the arm *c* is materially shorter than the length of the arm plus that of the finger, and said arms are separated by spaces of a width substantially equal to that of one of the arms, and, as a result, two corner beads having arms or legs of standard length can be made from a sheet metal blank of minimum width without waste and at a material saving in cost, which is highly important from a commercial view point. The corner bead may be made in sections of any desired length within limits.

Claims:

1. A metal corner bead section provided with a substantially flat body member folded at one edge to form a longitudinally extended bead and having arms extended from its other edge at an angle to said body portion and normally lying in the plane of said body portion with adjacent arms spaced apart by a distance substantially equal to the width of one of said arms, and which forms a bonding opening for plaster between the arms, fingers integral with said arms and struck therefrom and normally lying in the plane thereof, said fingers being folded substantially parallel with said arms and projected beyond the lower edge thereof to form therewith arms of a predetermined length but of different widths and to provide bonding openings for the plaster in the arms themselves.

2. A metal corner bead section provided

with a substantially flat body member having arms extended from one of its edges at an angle to said body portion and normally lying in the plane of said body portion with adjacent arms spaced apart by a distance substantially equal to the width of one of said arms, and which forms a bonding opening for plaster between the arms, fingers integral with said arms and struck therefrom and normally lying in the plane thereof, said fingers being folded substantially parallel with said arms and projected beyond the lower edge thereof to form therewith arms of a predetermined length but of different widths and to provide bonding openings for the plaster in the arms themselves.

3. A metal corner bead section provided with a substantially flat body portion having arms extended from one of its edges at an angle to said body portion and normally lying in the plane of said body portion with adjacent arms spaced apart to form bonding openings for the plaster between said arms, fingers integral with said arms and struck therefrom and normally lying in the plane thereof, said fingers being folded substantially parallel with said arms and projected beyond the lower edge thereof to form therewith arms of a predetermined length but of different widths and to provide bonding openings for the plaster in the arms themselves.

In testimony whereof, I have signed my name to this specification.

RUSSELL K. NASH.
